UNITED STATES PATENT OFFICE.

GEORGE HARNISH LAWRENCE, OF OWENSBORO, KENTUCKY.

OIL BURNER.

Application filed January 31, 1923. Serial No. 616,149.

To all whom it may concern:

Be it known that I, GEORGE HARNISH LAWRENCE, a citizen of the United States, and resident of Owensboro, in the county of 5 Daviess and State of Kentucky, have invented certain new and useful Improvements in Oil Burners, of which the following is a specification.

This invention relates to oil burners especially adapted for use in boilers and furnaces of various types.

Briefly stated an important object of this invention is to provide an oil burner having simple means whereby to preheat the oil so as to gasify the same and air substantially in combustion.

A further object is to provide an oil burner which may be conveniently applied to a boiler or furnace and which will operate with a minimum consumption of oil and in a highly efficient manner.

Other objects and advantages of the invention will be apparent during the course of the following description.

25 In the accompanying drawings, forming a part of this application and in which like numerals are employed to designate like parts throughout the same,

Figure 1 is a side elevation of the improved oil burner applied.

Figure 2 is a plan view thereof, the forward portion of the burner being shown in section.

Figure 3 is a vertical longitudinal sectional view through the improved oil burner applied.

Figure 4 is a vertical transverse sectional view taken on the line 4-4 of Figure 3.

In the drawing wherein for the purpose 40 of illustration is shown a preferred embodiment of the invention the numeral 5 generally designates a tubular body cast or otherwise formed and having a fuel conduit 6 extending longitudinally through the chamber 7 therein, all of which is illustrated 45 in Figure 3.

The forward portion of the fuel conduit or nozzle 6 is formed with a reduced opening and a valve seat 9 arranged at the rear 50 end of the reduced opening cooperates with the valve 10 in controlling the outlet of the fuel.

Figure 3 further illustrates that the rear portion of the valve 10 is formed with a hand wheel 12 by means of which the valve

may be manually regulated. The rear portion of the nozzle 6 is formed with a T-shaped coupling 13 having connection with a pipe 14 which communicates with a longitudinally extending gasifying channel 60 or duct 16 in the lower portion of the tubular body. The forward portion of the longitudinal duct 16 communicates with an annular duct or passage 18 wherein the liquid fuel is subjected to the heat resulting from 65 the combustion of the fuel at the forward portion of the burner.

The annular gasifying chamber is supplied with liquid fuel by means of a longitudinally extending duct 20 in the upper 70 portion of the tubular body, the said longitudinally extending duct having communication with a fuel supply pipe 22 which may extend from a suitable point of supply.

With reference to Figures 2 and 3 it will 75 be observed that the rear portion of the body is provided with a downwardly extending inlet branch 30 having a gate valve 31 by means of which a supply of air is regulated and the gate valve 31 or the butterfly valve 80 31 as the case may be is controlled by means of a hand wheel 33.

With reference to the foregoing description taken in connection with the accompanying drawings it will be seen that the fuel oil is supplied to the longitudinally extending duct 20 from where it flows into the annular heating chamber 18. The combustion at the forward end of the burner highly heats the oil contained in the annular chamber 18 and gasifies the same. As the liquid fuel is gasified in the engine chamber 18 it flows rearwardly in the longitudinally extending duct or chamber 16 and then through the pipe 14 into the tubular nozzle 6. The position of the valve 10 regulates the quantity of gas discharged for combustion and the arrangement illustrated provides for the efficient mixture of air and fuel for combustion.

The improved burner may be attached to a furnace 40 by means of attaching bolts 41 which extend through the openings in an annular flange 42 surrounding the intermediate portion of the body. The burner 105 preferably terminates at the inner side of the furnace as illustrated in Figure 3.

Having thus described the invention, what is claimed is:—

1. An oil burner comprising a tubular 110

body having its rear portion formed with a laterally extending air inlet branch, a longitudinally extending nozzle arranged in said body and having its forward portion formed 5 with a reduced opening and an annular valve seat, a valve cooperating with said seat and terminating rearwardly of said nozzle, a fuel supply pipe connected to the rear portion of said nozzle, said tubular body 10 being provided with internal longitudinally extending fuel passages, one of which communicates with said fuel supply pipe, a liquid fuel supply member connected to the other longitudinally extending passage, the 15 forward portion of said tubular body being provided with an annular gasifying chamber communicating with said first and second named passages and subjected to the heat of the products of combustion, a valve

controlling the supply of air to said inlet 20 branch, and means to regulate said valve.

2. An oil burner comprising a tubular body having its forward portion provided with an internal gasifying annular chamber, said body also being provided with an upper fuel supplying conduit communicating with said annular chamber and being provided at its lower side with a rearwardly projecting longitudinally extending internal 25 gasifying conduit, a liquid fuel supply member connected to said inlet conduit, a fuel dispensing pipe connected to the rear portion of said rearwardly extending conduit and having communication with the interior 30 of the body, and fuel control means arranged 35 within the body.

GEORGE HARNISH LAWRENCE.
